[57] CLAIM

The ornamental design for a handle for a stapling machine, as shown and described.

DESCRIPTION

FIG. 1 is a top plan view of a handle for a stapling machine showing my new design;

FIG. 2 is a side elevational view taken from the left side of FIG. 1;

FIG. 3 is a front elevational view thereof;

FIG. 4 is a side elevational view taken from the right side of FIG. 1;

FIG. 5 is a rear elevational view thereof;

FIG. 6 is a bottom plan view thereof; and

FIG. 7 is a perspective view thereof, the environmental structure shown in broken lines being for illustrative purposes only.
